FLUSH TANK WITH OUTLET SIPHON

William J. Collison, Bakersfield, Calif.

Original application November 25, 1936, Serial No. 112,806. Divided and this application April 8, 1937, Serial No. 135,787

3 Claims. (Cl. 4—42)

This invention relates to a flush tank with outlet siphon structure and it aims to provide an improvement upon those devices disclosed in Letters Patent issued to me No. 1,812,774 on June 30, 5 1931, No. 1,842,715 on January 26, 1932 and 1,933,416 on October 31, 1933.

The present application is a division of my application Serial No. 112,806 filed November 25, 1936 for a Flushing device and the ball cock structure disclosed herein, is the subject matter of such pending application.

It is particularly aimed to provide an improved structure using two inverted U-shape traps or chambers vented with two breather tubes and one 15 upright U-shape trap or chamber constructed and arranged without moving parts to act as a valve to control the flow of water from the flush tank to the toilet bowl.

It is further aimed to provide in connection with 20 the novel trigger arrangement and ball cock structure constituting the subject matter of said application 112,806, novel adjustment screws on the ball cock and breather tubes on the flushing unit to synchronize the action of the ball cock and 25 flushing unit so as to properly control the flow of water into the flush tank and out of the flush tank through the flushing unit to the toilet bowl, and to provide such a construction having the advantages set forth, which may be incorporated 30 within the flushing tank, and which may be adapted to practically all standard flush tanks and toilet bowls without change therein, to effect cheaper manufacture, quieter action and better appearance.

35 The more specific objects and advantages will become apparent from a consideration of the description following taken in connection with accompanying drawings illustrating an operative embodiment.

40 In said drawings:

Figure 1 is a view showing my improvements in side elevation and as mounted within a flush tank, the latter being shown in transverse section;

45 Figure 2 is a detail vertical sectional view taken through the trap device;

Figure 3 is a vertical sectional view taken on the line 3—3 of Figure 2;

50 Figure 4 is a transverse sectional view taken on the line 4—4 of Figure 2;

Figure 5 is a transverse sectional view taken on the line 5—5 of Figure 2;

55 Figure 6 is a detail enlarged side elevation of the link connection between the trigger and inlet valve lever;

Figure 7 is a detail section taken on the line 7—7 of Figure 6, and

Figure 8 is a detail side elevation of the said lever.

Referring specifically to the drawings wherein like reference characters designate like or similar parts, 10 designates an ordinary or conventional water closet flush tank in the bottom wall of which a water supply pipe 11 is connected, rising to a suitable height and mounting a bracket 12 having a depending outlet or flush pipe 13, terminating above the bottom wall of the tank 10. The supply of water through the pipe 11 is normally cut-off at a conventional valve 14 under control of a vertically slideable plunger 15, suitably mounted in the bracket 12 and engaged by an adjustable screw 16 carried by a lever 17 and pivoted as at 18 to an arm 19 of the said bracket 12.

Said bracket 12 also has another arm at 20 to 20 which is pivoted at 21, a lever 22 from which an arm 23 extends and carries a float or ball 24 at its free end. The lever or trigger 22 carries an adjustable set screw 25 for co-action with the free end of the lever 17. An operating ring 26 25 is pivoted at 27 to the trigger lever 22 and to such ring links 28 are pivoted at 29 and such links by means of a screw or the like 30, are pivotally and slidably connected to the lever 17 through an elongated slot 31 of the lever 17. 30

Said ring 26 is adapted to be actuated by a push button or lever arrangement from without the tank.

A trap unit generally designated 32 is suitably mounted within the tank 10, having its outlet or 35 flush pipe 33 extending water tight through the bottom wall of the tank and leading to a toilet or the like. The inlet to the trap device at 34 is above the bottom wall of the tank and a tortuous passageway is provided through the trap 40 device providing a trap as at 35, an inverted trap as at 36, and an air chamber 37.

A refill tube 38 is connected to the trap device, extending upwardly therefrom, thence downwardly, and thence upwardly terminating within 45 the lower end of the pipe 13. Also connected to the trap device and communicating with the air chamber 37 is a breather pipe 39. Adjacent the breather pipe 39 is a second breather pipe 40, extending above and thence downwardly and being connected to the trap device in communication with the inverted trap or chamber 36. It will be noted that the inlet or lower end of the breather pipe 39 is slightly above the inlet or 50 55

lower end of the breather pipe 40 and the latter is slightly above the lowest water level.

In the description of the operation of the device, three water levels will be referred to as have been indicated in Figure 1 of the drawings, namely high water level, normal water level, and lowest water level. The trigger ring 26 is actuated by a push button or lever arrangement or otherwise from without the tank which raises the same,

10 breaking the lock between the ring 26 and links 28, which releases the pressure on the lever 17, allowing the water to enter the tank 10 through the pipe 13. This causes the water to rise in the tank 10 from the normal water level to the 15 high water level, at which point it displaces the air in chamber 36, which fills with water through the inverted U-trap 37. The water then sets up siphonic action through the U-trap 35 over the inverted U-trap 36, the water travelling thence 20 down through the regular flush pipe 33 into the toilet bowl. As the water level lowers in tank 10, the float ball 24 drops with the water level causing the ring trigger plate 26 and connecting links 28 to automatically fall into locking position.

25 When the water level falls below the lower end of breather pipe 39, the upper end of which opens into the chamber or trap 37, air enters pipe 39 and fills chamber 36. A short interval later, the water falls below the open end of the breather pipe 40 which extends above the high water level, and air enters chamber 39. An inverted U-trap is formed returning down and opening into the trap or chamber 36 which breaks the siphonage pull at this point and leaves U-trap 35 filled with 30 water which seals chamber 36 and causes an air pressure to build up therein as the water level rises in the inlet 34 of the trap device and in the tank 10 to a predetermined normal water level which is regulated by the adjustment screw 16.

40 The adjustment screw 25 presses down on the lever 17 and regulates the interval of time which float ball 24 remains at the lowest position, which allows chambers 27 and 26 to become filled with air before the rising water level seals chamber 36 by rising above the lower ends of breather pipes 39 and 40. Refill pipe 38 extends below the lowest water level and above the highest water level, forming a U-trap at the lowest point. Water entering the flushing unit through the refill pipe 38 flows into U-trap 35, causing the water level therein to rise, overflowing through the second inverted U-trap 36 and thence through the flush pipe 33 to refill the toilet bowl.

45 It will be noted that the adjusting screw 16 slows down the ball cock 24 at the lowest water level, such hesitation allowing the air chambers to refill with air. The air tubes or vents 39 and 40 are breaker vents and also silencers as they do not make a hissing noise. The slotted connection at 30-31 and screw 16 co-act as they allow the feed of the incoming water to be slowed down, say for a few seconds, to allow the air chambers to refill with air.

50 It will be noted that the plunger 15 is loose and not connected to the ball cock valve at 14. The water pressure opens the ball cock valve when the lever 17 with the screw 16 disengages it. Back siphonage will close it shut and tight.

55 Various changes may be resorted to provided they fall within the spirit and scope of the invention.

I claim as my invention:—

1. A device of the class described having a flush tank, a water supply pipe rising therein, said pipe having a downwardly extending discharge pipe, float control means, a valve controlled by the latter to govern the supply of water through the first mentioned pipe, a trap device within the tank having a flush pipe leading therefrom, said trap device having an inlet below the water level and a passageway therefrom to the flush pipe of connected portions of U-shape one above the other, a refill pipe extending from adjacent the lower end of the discharge pipe to the upper portion of the interior of the trap device, said refill pipe adjacent said lower end of the discharge pipe being upturned and engaging in the discharge pipe, a breather pipe communicating with the interior of the trap device at the upper portion, and a breather pipe communicating with the interior of the trap device at the upper portion of the other U-shape passage therein. 5

2. A device of the class described having a flush tank, a water supply pipe rising therein, said pipe having a downwardly extending discharge pipe, float control means, a valve controlled by the latter to govern the supply of water through the first 25 mentioned pipe, a trap device within the tank having a flush pipe leading therefrom, said trap device having an inlet below the water level and a passageway therefrom to the flush pipe of connected portions of U-shape one above the other, 30 a refill pipe extending from adjacent the lower end of the discharge pipe to the upper portion of the interior of the trap device, said refill pipe adjacent said lower end of the discharge pipe being upturned and engaging in the discharge 35 pipe, a breather pipe communicating with the interior of the trap device at the upper portion, and a breather pipe communicating with the interior of the trap device at the upper portion of the other U-shape passage therein, the second 40 mentioned breather pipe having its lower end below the lower end of the other breather pipe, said second mentioned breather pipe being U-shaped and extending above the high water level.

3. A device of the class described having a flush 45 tank, a water supply pipe rising therein, said pipe having a downwardly extending discharge pipe, float control means, a valve controlled by the latter to govern the supply of water through the first mentioned pipe, a trap device within the 50 tank having a flush pipe leading therefrom, said trap device having an inlet below the water level and a passageway therefrom to the flush pipe of connected portions of U-shape one above the other, a refill pipe extending from adjacent the 55 lower end of the discharge pipe to the upper portion of the interior of the trap device, said refill pipe adjacent said lower end of the discharge pipe being upturned and engaging in the discharge pipe, a breather pipe communicating with the interior of the trap device at the upper portion, and a breather pipe communicating with the interior of the trap device at the upper portion of the other U-shape passage therein, the second 60 mentioned breather pipe having its lower end below the lower end of the other breather pipe, said second mentioned breather pipe being U-shaped and extending above the high water level, the refill pipe also extending above the high water level. 65
